UNITED STATES PATENT OFFICE

ROBERT B. COLEMAN AND WILLIAM R. HAMILTON, OF LOS ANGELES, CALIFORNIA, AS
SIGNORS TO BY-PRODUCTS FUEL MACHINE CO., OF LOS ANGELES, CALIFORNIA

MATERIAL COMPRESSOR

Application filed April 24, 1928. Serial No. 272,418.

Our invention relates to material compressors of the general type shown and described in Letters Patent No. 1,260,514 of March 26, 1918, and Letters Patent No. 1,541,901, issued June 16, 1925, and in which sawdust, shavings, chips, straw pulp and the like can be compressed into blocks, briquettes and the like and tied with a wire and discharged for use as fuel, the feeding, compressing, tying and releasing or discharging all being done automatically.

The present invention has to do more particularly with improved mechanism for operating the mechanical elements which hold the compressed material at the lower end thereof, which break off that portion to be formed into the briquette or block, which operate the wire tying means and which release the formed briquette from the machine.

In this machine we have provided a plurality of revolving cams which intermittently operate the various mechanical devices to cause them to perform their respective functions, thus making for greater accuracy in the operation of the machine.

In order to explain our invention, we have shown on the accompanying three sheets of drawings such mechanism as is involved in the present case and which embodies our invention, which we will now describe.

Figure 1 is a side elevation of the lower portion of a compressing machine, in which our invention is embodied;

Figure 2 is a side elevation taken on line 2-2 of Fig. 1;

Figure 3 is a side elevation of a portion of the mechanism, taken on line 3-3, and showing the cam which operates the switches which control the wire twisting means;

Figure 4 is a fragmentary vertical sectional view, taken on line 4-4 of Fig. 1;

Figure 5 is a plan view of the table having the grooves or runways for the pins of the wire twisting means, showing the switches operated by the cam for guiding said pins from the outer to the inner grooves, said view being taken on line 5-5 of Fig. 3.

Referring now more in detail to the drawings, we will describe that portion of the

mechanism which has to do with our invention.

The material to be compressed is fed downwardly through a feed pipe or chute 10, connected with a hopper-like body 11, in which is a revolving feeder 12, on a shaft 13, driven by beveled gears 14 and 15, sprocket gears 16 and 17, connected with sprocket chain 18, on shaft 19. The operation of this feeder 12 is timed to make a sweep of material from one side of the hopper body 11, over to the path of the vertical plunger 20, each time said plunger is raised, whereby said plunger forces said material down into the forming die 21, suspended from the main frame member 22, of the machine. The means for operating the plunger is not shown, as it forms no part of the present invention, but the lower end of said plunger is shown, and the feeder is indicated in Figs. 1 and 2, and this mechanism operates to definitely and certainly supply a quantity of material to the die, as will be clear from said showing.

At the lower end of the die 21, where the formed or compressed material emerges, are oppositely disposed bearing shoes 23, pivotally mounted on a bracket 24, for each, with springs 25 for yieldingly bearing against the lower end of the protruding compressed material to hold it together as it is forced downwardly by the intermittent strokes of the plunger 20 above. A wire 26 is extended through the die 21, one at each side and down under the lower end of the formed material with their meeting ends twisted together at the lower end of the compressed material, and as the briquette is formed said wires are brought together above the length of the compressed material broken off to form the briquette and twisted and cut. This mechanism and operation is fully illustrated and described in the patents referred to and forms no part of the present invention, and is only shown partially to connect up the invention of this application. Said wires extend around the briquette longitudinally and are drawn in as the material is forced downwardly.

As the compressed material is thus com-

pressed and forced downwardly through the die, there are two oppositely disposed jaws, pivotally mounted intermediate their ends, as at 29 and 30, with their lower ends, 27 and 28' extended downwardly and having connected thereto two links, 31 and 32, the other ends of which links are pivotally connected to a rocker plate 33, pivotally mounted, as at 34, to the lower end of a bracket 35, secured to a vertically movable support 36, formed as a part of a vertical bar 37, moving in two guides 38 and 39, and provided with two vertically spaced rollers, as 40 and 41, adapted to be engaged and raised and lowered by means of a cam 42, on a main cam shaft, designated 19.

At the opposite side of said projecting support 36, is a second bar or member, 43, Fig. 4, to which the opposite sides of said jaws 27 and 28 are pivotally connected, as at 29' and 30', thus said jaws are each supported pivotally at opposite sides. The supporting bracket 35, Fig. 2, in order to give the necessary space for the jaws to operate between said bracket 35 and the other supporting member 43, at the opposite side, is bent outwardly to an angle, as at 35', while the member 43 projects straight from said support 36, on the reciprocating vertical bar 37. Said member 43 and said bracket 35 are secured to said support 36, by two bolts, as 44, 44. As the cam 42 is thus operated by the shaft 19, said vertical bar 37 is raised and lowered, and through its connections the jaws 27 and 28 are raised and lowered for the purpose of biting off a portion of the lower end of the compressed material being forced downwardly through the die 21. Said jaws are opened and closed by means of the links 31 and 32, and the rocker plate 33 in the following manner: To the upper end of said rocker plate 33 is connected an operating bar 45, the opposite end of which arm is extended through the lower end of a member 46, with a coiled spring 47 between said member 46 and a collar 47', on said bar 45, and a second collar 48 on the outer end of said bar 45, having its contact face rounded, as at 48'.

The member 46, has an outwardly projecting loop portion 46' around the cam shaft 19, with two cam rollers 49 and 50, mounted thereon at the opposite ends of said loop portion 46', with a cam 51, on the cam shaft 19, operating between said cam rollers and operating to move said member 46, and the operating bar 45 horizontally and intermittently, as will be clear from Fig. 2. A guide bar 52, is connected to the upper end of the member 46, and this moves through a guide bracket 53, for holding the parts steady and in alinement, inasmuch as the bar 45 will have a varied movement as the rocker plate 33 rocks on its pivotal support 34. Thus by the operation of the cam

51, on the main cam shaft 19, the jaws 27 and 28, are moved on their pivotal supports at 29 and 30, and 29' and 30' to close the jaws together on the protruding material and then when said jaws 27 and 28, with their supports 35 and 43, are moved downwardly, a portion of said compressed material is broken off from the main part thereof being forced down through the die 21. Said jaws are shown in their open positions in full lines, Figs. 2 and 4, and in their down position in light broken lines in said Fig. 4. These jaws for biting off the material is old in the patents referred to, but the improved means for operating them with revolving cams is new and has greatly increased the accuracy and efficiency of the machine.

The down position of said jaws 27 and 28, after they have been closed in on the protruding material from the die 21, is below the table, designated 54, at which level the tying of the wires is done, after the briquette has been bitten off and pulled down, the wires being pulled down with it. The wires are twisted by the revolving of the table, as fully described in the patents referred to. The tying elements are moved in to the wires while they are revolving and after the wires are twisted they are moved outwardly again. This action is accomplished by concentric grooves 55 and 56, shown in the plan view, Fig. 5, and it is the new means for operating the switch elements 57 and 58, for changing the positions of the tying elements that forms part of the present invention. The present invention makes it possible to operate these switch elements by a cam on the main cam shaft, as in the other operations hereinbefore described.

A yoke 59, Figs. 3 and 5, is connected to simultaneously move the switch elements 57 and 58, to the three positions indicated in full lines and light broken lines, Fig. 5, said yoke having a stem or operating rod 59', connected to an operating member 60, Fig. 3, having a loop 61 therein through which the main cam shaft 19 extends. On said operating member 60 is a cam roller 62, positioned to run in an internal cam 63, said cam having a bulge 63^a at one side thereof, which operates as said cam is revolved to move said member 60, and said yoke 59 to an extreme position, whereby to move the switch members 57 and 58 outwardly, while the concentric portion of said internal cam 63 moves said switch elements to neutral position, shown in full lines, Fig. 5, and an indent 63^b in said internal cam 63 operates to move said yoke outwardly, and thereby move said switch elements to the other extreme position, shown in light broken lines. We do not show the wire twisting and cutting mechanism, as it is no part of this invention, and as the mechanism is the same general construction and arrangement as shown in the

5 patents referred to, we have only shown that which we consider a part of the present invention, namely the revolving cams for operating the various mechanisms herein described, for it will be seen from the foregoing description and the showing on the drawings, that with a single cam shaft, with three revolving cams thereon, we are able to operate the biting jaws 27 and 28, to bite the 10 material and to pull it down, and to control the switch elements which in turn control the wire twisting means shown in the patents referred to. This makes it possible to properly time the various operations and to make 15 them positive and efficient.

The main cam shaft 19 is provided with a clutch 64, moved by means of a lever 65, into and out of driving engagement with a clutch element 66, connected with a drive 20 gear 67, and meshing with a pinion not shown but driven through a sprocket chain 68, from the main driving mechanism above, a portion only of a large gear 69 being shown. It is not deemed necessary to show more of this 25 mechanism, as it forms no part of the present invention and is only referred to as it is related to the main cam shaft 19.

Thus we have provided a main cam shaft with a series of operating cams 42, 63 and 51, 30 thereon and operated thereby for operating the jaws 27 and 28 up and down, closing and opening said jaws to bite the material from the main stick being forced through the die, and for controlling the switch elements 57 35 and 58, which in turn control the wire twisting and cutting mechanism, the movement of the switch elements, however, being the only new feature involved herein. These with the intermittent feed of the material by 40 the feeder 12, also operated from said main cam shaft 19, through the sprocket chain 18, constituting the main features of improvement over the old machines of the prior patents.

45 We do not, however, limit our invention to the details of construction and arrangement here shown for illustrative and descriptive purposes, except as we may be limited by the hereto appended claims.

50 We claim:

1. In a compressing machine of the character referred to, having a die and plunger adapted to be operated to force material into and through said die, a pair of jaws mounted to be moved vertically and to be opened and closed upon material protruding from said die, the combination of a main cam shaft, a cam operated by said shaft for raising and 55 lowering said jaws intermittently, a cam on said shaft for opening and closing said jaws to bite into said material, a feeder for feeding material intermittently to said die, and operating connections from said cam shaft 60 for operating said feeder, whereby said several mechanisms are operated in synchronism.

2. In a compressing machine of the character referred to, having a die and plunger adapted to be operated to force material into and through said die, and tying means for tying said material, a feeder for intermittently feeding material to said die, a pair of jaws pivotally mounted and movable vertically bodily at opposite sides of said material as it is forced from said die, the combination of a main cam shaft, a cam operated by said shaft for raising and lowering said jaws, a cam operated by said shaft for opening and closing said jaws to bite into said material and to pull it away from said die as said jaws are moved downwardly bodily, a cam on said shaft for controlling the tying mechanism, and operating means from said shaft for operating said feeder. 70 75 80 85

3. In a material compressing machine, having a pair of jaws movably mounted to open and close upon material compressed, said jaws being mounted to be moved vertically, the combination of a cam shaft, a revolving cam on said shaft for raising and lowering said jaws, a cam on said shaft for opening and closing said jaws to bite into said material, said cams being operable in synchronism to close said jaws upon said compressed material and to move them downwardly thereafter, whereby to pull a part of said material with them. 90 95 100

4. In a material compressing machine, having a pair of jaws at opposite sides of the path of the compressed material, means for supporting said jaws pivotally, said means being movable vertically, the combination of a cam shaft, a cam on said shaft for raising and lowering said supporting means and said jaws, a cam on said shaft for opening and closing said jaws to bite into material compressed and protruding therebetween, whereby said jaws are automatically operated to bite into said material and to pull it down with them as they are moved downwardly. 105 110

5. In a material compressing machine, having a die, a plunger for forcing material into said die, a feeder for intermittently feeding material to said die, a pair of jaws in alignment with said die to receive material in compressed form from said die, said jaws being movably mounted to open and close upon material protruding from said die, said jaws being movable vertically to and from said die, the combination of a cam shaft for operating said jaws, said cam shaft having cams for raising and lowering said jaws and for opening and closing them in synchronism, whereby to bite into material protruding from said die and to pull it downwardly as they are moved bodily, and operating connections from said shaft for 115 120 125 130

operating said feeder in synchronism with the movement of said material through said die.

6. In a material compressing machine, having a die, a plunger for forcing material into said die, a feeder for intermittently feeding material to said die, a pair of jaws in alignment with said die to receive material in compressed form from said die, supporting means for said jaws, pivotal mountings for said jaws thereon, means for raising and lowering said supporting means to raise and lower said jaws therewith, and means operating in synchronism therewith to open and close said jaws upon material compressed through said die and to pull it downwardly as said jaws are moved bodily downwardly following their closing movement, and means for operating said feeder from said jaw operating means.

7. In a material compressing machine, having a die, a plunger operable vertically therein to compress material in said die, a hopper-like body around said plunger and the mouth of said die, a feeder revolvably mounted therein at one side of said plunger and operable to intermittently, with each revolution, to sweep material to the mouth of said die, a pair of jaws pivotally and movably mounted at opposite sides of the path of material forced from said die, the combination of a cam shaft, a cam thereon for operating said jaws on their pivots to bite into said material, a cam on said shaft for raising and lowering said jaws in synchronism with their biting action, and means from said cam shaft for operating said feeder in synchronism with the plunger movement into said die for forcing said material therethrough.

Signed at Los Angeles, Los Angeles County, California, this 16th day of March, 1928.
